EYEGGLASS CONSTRUCTION

George E. Nerney, Attleboro, Mass., assignor to
Bay State Optical Company, a corporation of
Maine

Application October 17, 1934, Serial No. 748,574

5 Claims. (Cl. 38—45)

This invention relates to an eyeglass construction and more particularly to the connection between certain parts thereof.

One of the objects of this invention is to provide a simple and thoroughly practical eyeglass construction. Another object is to provide a construction of the above nature having a minimum number of parts and capable of easy assembly. Another object is to provide construction of the above nature which may be readily and inexpensively manufactured in large quantities. A further object is to provide a construction of the above nature wherein certain parts may be readily disassociated for the purposes of replacement or repair. A still further object is to provide a construction of the above nature which is sturdy and durable under the strain of extended use. A still further object is to provide a construction of the above nature which is pleasing in appearance and which may be comfortably worn by the user. Other objects will be in part obvious and in part pointed out hereinafter.

The invention accordingly consists in the features of construction, combination of elements, and arrangement of parts, as will be exemplified in the structure to be hereinafter described, and the scope of the application of which will be indicated in the following claims.

In the accompanying drawing, in which is shown one of the various possible embodiments of this invention,

Figure 1 is a front elevation of an eyeglass mounting, certain of the parts thereof being broken away;

Figure 2 is a rear elevation of the mounting shown in Figure 1;

Figure 3 is a sectional elevation of the mounting taken along line 3—3 of Fig. 1.

Similar reference characters refer to similar parts throughout the several views of the drawing.

As conducive to a clearer understanding of certain features of this invention it might here be pointed out that in eyeglass frames or the like, and more particularly frames of the type in which non-metallic rims are associated with a metallic bridge, considerable difficulty is experienced in providing a connection between the rims and the bridge. For example, due to the character of the materials it is difficult to obtain a joinder of the parts which will not loosen after continued usage, such loosening being difficult and sometimes impossible to correct. Further, in these constructions it is difficult to provide parts such as rims and bridges which may be

readily interchanged after assembly without serious damage to one part or the other. Further difficulty is also encountered in providing a frame of the above nature which does not have certain fragile parts particularly susceptible to breakage. Another object of this invention is to provide a construction of the above nature in which the above-mentioned difficulties, in addition to many others, are successfully and efficiently overcome.

Referring now to the drawing, there is shown a pair of rims generally indicated at 10 and 11 (Figures 1 and 2) and a bridge generally indicated at 12, rims 10 and 11 being connected to bridge 12 in a manner hereinafter more fully described.

Rims 10 and 11 are provided with enlarged portions 13 and 14, respectively, portions 13 and 14 preferably being integrally formed on the rims and preferably being shaped to form a pair of nose guards 15 and 16. Thus the nose guards include projections 15a and 16a extending rearwardly from the rear plane surfaces of rims 10 and 11, preferably being integral therewith and having their opposed surfaces substantially convex or rounded and preferably roughened so that they may rest firmly and comfortably on the nose of the wearer.

As best shown in Figure 1, the tops of the rim portions 13 and 14 break sharply to gradually merge into the rims, thus forming in effect shoulders 18 and 19, the top surfaces of which are almost at right angles to the opposing surfaces of the nose guards. Immediately behind each of projections 15a and 16a I provide holes 20 and 35, respectively, extending through rim portions 13 and 14 and having their axes running substantially perpendicular to the planes of the lenses mounted in the rims.

The upper portion 21 of the bridge member 12 may be arcuate in form (Figures 1 and 2) preferably extending from rim to rim. The opposite ends of the bridge thence extend inwardly and downwardly in effect forming the arm portions 22 and 23 resting snugly against the peripheries of the rims and preferably spread from the front surfaces 10a and 11a thereof, as best shown in Figure 2. Immediately adjacent shoulders 18 and 19 the opposite end portions bend rearwardly and extend in directions substantially perpendicular to the general plane occupied by portion 21 and arm portions 22 and 23 of the bridge (Figures 2 and 3) to form the rear extensions 24 and 25 which rest firmly upon shoulders 18 and 19, respectively.

Next, the ends of bridge 21 again bend substantially at right angles to the axis of rear extensions to form the leg extensions 26 and 27, as more clearly shown in Figures 2 and 3. Leg extensions 26 and 27 rest firmly upon the rear surfaces of rim portions 13 and 14 and are also preferably in engagement with the rear sides of projections 15a and 16a, thus being, in effect, adjacent the junction between projections 15a 10 and 16a and the rims of the frame. Leg extensions 26 and 27 extend downwardly, as viewed in the drawing, to points adjacent holes 28 and 35 where they bend again to form the fastening portions 28 and 29 which extend forwardly through 15 the holes in a direction substantially perpendicular to the plane occupied by leg portions 26 and 27. As best shown in Figure 3, fastening portions 28 and 29 extend through the rim portions and may be secured in this position 20 in any suitable manner. For example, they are preferably threaded, and nuts 31 and 32 are threaded thereon (Figures 1 and 3), thus securing the fastening portions firmly in position, while allowing for removal therefrom should the 25 necessity arise.

The particular shape of bridge 21 and the portions thereof in engagement with rims 13 and 14, all as described above, make for an extremely practical and firm connection between the bridge 30 and the rims. In practice, frames of this general character are often subjected to considerable rough usage which is particularly damaging to the points of connection between the various parts. For example, the rims are often twisted, thus to 35 strain the points of connection between the bridge and the rims. Where the rims are formed from non-metallic material and the bridge from metal, these connections are often the most vulnerable spots on the frame. However, due to the particular shape of bridge 21, the connection between the bridge and the lens is reenforced regardless of the strains, as, for example, twisting, 40 exerted on the frame.

If, for example, the rims are spread outwardly, 45 portions 22 and 23 abut against the peripheries of the rims thus guarding against any damaging relative movement between the bridge and the rims anywhere in the vicinity of holes 28 and 35. Again, if rim 11 is twisted forwardly about its 50 transverse axis, as viewed in Figure 1, rear extension 25 abuts against shoulder 19 while leg portion 26 abuts against the rear face of rim 10, both of these portions of the bridge tending to offset any forces exerted in the vicinity of the holes 28 and 35. Other strains exerted on the 55 bridge and rim connections of my frame would be materially offset by corresponding portions of the bridge in engagement with portions of the rims. The fact that bridge 21 comprises so many individual portions running in so many different directions to remain in close contact with the irregular portions of the rims located about the nose guards 15 and 16 thus makes for a firm and durable connection between these parts of 60 this frame.

It will thus be seen that I have provided a 65 thoroughly practical, efficient and durable construction in which the several objects described above, as well as many others, have been successfully achieved.

As many possible embodiments may be made 70 of the above invention, and as many changes

may be made in the embodiment above set forth, it is to be understood that all matter hereinbefore set forth or shown in the accompanying drawing is to be interpreted as illustrative and not in a limiting sense.

I claim:

1. In eyeglass construction, in combination, a pair of rims having thickened portions forming sections of nose guards and a pair of rearwardly extending wing-like members also forming sections of said nose guards, the tops of said thickened portions extending inwardly to form shoulders, a bridge having a top section extending from one rim to the other rim and end portions including sections extending downwardly along said rims to said shoulders, thence extending rearwardly in engagement with said shoulders, thence extending downwardly along said thickened portions and adjacent said projections and thence extending forwardly through said rims, and means securing said bridge in said position.

2. In eyeglass construction, in combination, a pair of non-metallic rims, each of said rims having a bore extending therethrough perpendicular to a plane passing through said rims, a bridge member having a top section extending between said rims, arm portions extending downwardly engaging portions of the periphery of said rims, angular portions extending downwardly from the ends of said arm portions, said angular portions extending around to the rear surfaces of said rims and thence forwardly through said bores, and means to secure said bridge to said rims.

3. In eyeglass construction, in combination, a pair of rims, a pair of projections extending from said rims and including shoulder portions thereon, a bridge including a portion extending between said rims, and arm portions including sections extending downwardly adjacent said rims to said shoulders, thence extending rearwardly in engagement with said shoulders, thence extending downwardly engaging the rear surfaces of said projections and thence extending forwardly through said rims, and means securing said bridge in said position.

4. In eyeglass construction, in combination, a pair of rims, a pair of projections extending from said rims having a pair of shoulders, a bridge having a top section extending from one rim to the other, said top section having its ends abutting against the peripheries of said rims, and sections extending downwardly from said top section to said shoulders and following and engaging said rims, thence extending around said projections to the rear surfaces thereof, thence forwardly through said projections, and means securing said bridge to said rims.

5. In eyeglass construction, in combination, a pair of non-metallic rims lying in substantially the same plane and spaced from each other, and a metallic bridge member comprising a transverse portion bridging the space between said rims and having its ends abutting against the peripheries of said rims, arm portions depending from the opposite ends of said transverse portion and fitting firmly against the peripheries of said rims and angular portions extending from the ends of said arm portions passing through said rims in directions substantially perpendicular to the plane of said rims.

GEORGE E. NERNEY.
